UNITED STATES PATENT OFFICE.

JOHN K. BERGMARK, OF CADILLAC, MICHIGAN.

CHAIR.

1,112,969.

Specification of Letters Patent.

Patented Oct. 6, 1914.

Application filed October 25, 1912. Serial No. 727,752.

To all whom it may concern:

Be it known that I, JOHN K. BERGMARK, a subject of the King of Sweden, and a resident of the city of Cadillac, in the county 5 of Wexford and State of Michigan, have invented certain new and useful Improvements in Chairs, of which the following is a specification.

My invention relates to furniture and has 10 particular reference to an improvement in chairs.

The object of the invention is to provide a simple type of dining room chair convertible into a reclining chair adapted for 15 use after dinner, say, on the veranda as a comfortable reclining chair.

With this object in view the invention consists in the novel construction of chair, its combination and arrangement of parts, 20 all as hereinafter described in detail, illustrated in the accompanying drawing and incorporated in the appended claims.

In the drawing—Figure 1 is a perspective view of a chair embodying my invention. Fig. 2 is a side elevation showing the back of the chair in reclining position.

In the several views 2 represents the seat, 3 the back provided with legs or extensions 4 and 5 and 6 the chair legs. The lower 30 ends of the legs 4 and 5 are pivoted on pivots 7 and 8 in holes 9 and 10 which pass through the chair seat at an inclination so as to form rear rests for said chair which are parallel to the arms when the latter are 35 tilted backward the full extent of the backward tilting movement. As shown the arms 4 and 5 project a short distance below the chair seat and, preferably, to one of these arms and to one of the chair legs a coiled 40 spring 11 is attached and tensioned to pull the back toward its normal or nearly upright position shown in Fig. 1. A rod 12 is revolvably mounted on staples 13 and 14 on the underside of the seat. Extending at 45 right angles from the ends of this rod are arms or struts or braces 15 and 16 which normally support the arms 4 and 5 against backward tilting. In the braces 15 and 16 are a series of holes 17 and 18 through which 50 pins may be inserted to form stops against which the lower ends of the arms 4 and 5 may rest when it is desired to support the back at an inclination intermediate of the 55 positions in which it is shown in Figs. 1 and 2. The lower ends of the arms 4 and 5

are normally supported against the ends of the braces 15 and 16 when the chair is used as a dining room chair. A spring 19 coiled around the rod 12 and having ends 20 and 21 secured to, respectively, the chair seat and the brace 16 is tensioned to turn the rod 12 to raise the arms or braces 15 and 16 into engagement with the lower ends of arms 4 and 5 and thereby make the engagement automatic when the chair back is pulled 60 forward toward its raised position as in Fig. 1. A forwardly projecting lever arm 22 on the rod 12 serves as a handle upon the rod whereby it may be turned to release the braces 15 and 16 from the arms 4 and 5 by swinging said braces downward, or, in other words, by pressing the lever upward. The location of the lever is such as to make 65 this very convenient, the lever being at the edge of the chair that is naturally grasped 70 by the sitter.

The tension of the spring or springs tending to draw the back to its normal position may be varied from just sufficient to swing the back to a resistance which offers 80 a partial support against the sitter's pressure against said back. Hence if the sitter bears against the back but lightly it may be rocked to and fro, and when the sitter leaves the chair it will automatically assume 85 its rigidity as a whole, or as a dining room chair. Seen from the top it presents no mechanism and has all the simplicity of the plain chair with the exception of the extension of the holes for the 90 arms 4 and 5, which extensions are in the rear of the arms in their normal position. Various devices for permitting the tilting of the back have been provided, but they have uniformly failed to preserve substantially 95 intact the simplicity and usual appearance of the dining room chair and the cost of production has usually been prohibitive so far as the purpose of the present invention is concerned.

The provision of holes for pin stops in the braces is to adapt the chair for some possible special purpose where, for instance, it is desired to adjust the back for a sick person at an inclination intermediate of its 105 normal and extreme tilting, and is not designed for ordinary use. The usual ratchet bar would serve such intermediate adjustments better, but would involve a mechanism and construction which would defeat 110

the purpose of providing an armless dining room chair with the tilting feature as well as with the normal rigidity of the back. The rod, its braces and the lever or arm 5 for turning the rod and braces, may be conveniently formed out of a single heavy wire or light rod, by bending the wire over on itself to form the braces, and therefore obviating the material increase in expense that 10 this invention, among other things, is designed to overcome in chairs of this type.

The coiled springs attached to the lower ends of the arms 4 and 5, either or both, and to the rear chair legs are staple articles 15 of commerce, as is also such springs as the coiled spring 19, and add but a trifle to the cost of the ordinary dining room chair.

The construction of the brace or braces for supporting the legs 4 and 5 in normal position, their position underneath the chair seat and the arrangement to connect same with the portion of the back projecting beneath the seat, may, of course, be varied in

numerous ways without departing from the spirit of my invention.

I claim as my invention—

The combination with a chair having openings through the rear portion of its seat, of a back having lever-arms which pass through said openings, are pivoted therein and project below said seat, pivoted struts which abut against the projecting portions of said arms and support same in a substantially rigid and normally raised position, means for swinging said struts, and means causing an automatic engagement of said struts and arms and the raising of said back to its normal position.

In testimony whereof I have hereunto set my hand in the presence of two subscribing witnesses.

JOHN K. BERGMARK.
